UNITED STATES PATENT OFFICE.

FRED B. COREY, OF SCHENECTADY, NEW YORK, ASSIGNOR TO GENERAL ELECTRIC COMPANY,
A CORPORATION OF NEW YORK.

SIGNAL.

No. 882,554.

Specification of Letters Patent. Patented March 24, 1908.

Application filed February 17, 1906. Serial No. 301,584.

To all whom it may concern:

Be it known that I, FRED B. COREY, a citizen of the United States, residing at Schenectady, county of Schenectady, State of New York, have invented certain new and useful Improvements in Signals, of which the following is a specification.

My invention relates to signals for electrically-operated roads, and its object is to provide a signal having certain advantages with respect to reliability and efficiency not heretofore obtained.

In electrically-operated roads in which it is desired that the rails should form the block circuits for the signal system and also act as return conductors for the power-current it is the practice to employ for the signal circuits a kind of current different from that of the power-circuit. For instance, if direct-current is employed for propelling the trains, alternating-current may be employed for the signal circuits, or if alternating-current is employed for driving the trains, direct-current or alternating-current of a different frequency may be employed for the signal circuits. It has further been the practice on electrically-operated roads to employ power-current for operating the signals. This arrangement has certain disadvantages, since the power-current is at times liable to interruption. For instance, if a train is approaching a signal and the power-current is cut off by a circuit-breaker opening at the power-house, a signal operated entirely by power-current will go to danger and the motorman may consequently make an unnecessary emergency application of the brakes. The signal circuit, on the other hand, is not liable to occasional interruptions, so that the disadvantage above mentioned could be obviated by employing the signal current for operating the signals. On the other hand, when direct-current is employed for the power-circuit and alternating-current for the signal circuits a disadvantage would arise in using the signal circuit for operating the signals, since alternating-current magnets are not so efficient as direct-current magnets. Furthermore, it would necessitate transmitting a larger amount of signal current and would increase the liability to short-circuits and interruption of the circuit carrying the signal current.

By my invention I avoid both of the above mentioned disadvantages by employ-

ing the power-current for shifting the signal mechanism and the signal current for locking the signal in position when shifted. By this arrangement I am enabled on roads operated by direct current to employ direct-current magnets for shifting the signal, which is the part of the operation which requires much the greater part of the energy, while by using the signal current for the locking magnet, the signal is prevented from going to danger whenever the power-circuit is interrupted.

My invention further comprises a novel feature in the construction of the lock-magnet whereby its efficiency is greatly improved. In an ordinary alternating-current magnet, since the flux is constantly reversing and no flux at all exists at the instant of reversal, at this instant the magnet tends to release the signal.

In Patent No. 799,816, issued to H. E. White, September 19, 1905, is described a form of magnet in which the armature is not released upon a momentary reversal of the current through the energizing coil. The magnet described in that patent comprises two magnetic circuits, a movable armature adapted to be restrained when either magnetic circuit is energized, a coil connected to a source of current and adapted to energize one of said magnetic circuits, and means for energizing the second magnetic circuit upon the variation of current flow in the coil. I make use of the same principle described in that patent, but by modifying the construction I am enabled to obtain the two magnetic circuits in a single core. I accomplish this result by placing a short-circuited conductor across a portion of the pole-face of the magnetic core. The current in the energizing coil produces a current in the short-circuited conductor which modifies the phase of the flux in the portion of the core which it surrounds. Consequently, two magnetic fluxes displaced in phase from each other are produced at the pole-face of the core, and while one flux is at zero a certain amount of flux exists in the other portion of the core. With this construction the tendency of an alternating-current magnet to chatter or to release the signal is prevented.

My invention further comprises a feature applicable especially to three-position signals operated by solenoids. It is customary to provide a dash-pot for retarding the move-

ment of the signal mechanism so as to prevent violent shocks when the signal reaches the end of its range of movement. An air dash-pot offers an increasing resistance to movement as the piston approaches the inner limit of its travel, and a pull of a solenoid upon its core also increases as the core moves into the solenoid. Consequently, these two effects tend to balance each other when a single operating solenoid and air dash-pot are employed. When, however, two solenoids are employed with a three-position signal,—one to shift the signal from danger to caution, and the other from caution to clear—the curve of resistance of the dash-pot does not follow the curves of the pulls of the two solenoids. Consequently an uneven retarding effect is produced.

By my invention I employ two separate dash-pots for such a signal connected to the cores of the respective operating magnets. With this arrangement each dash-pot may be designed to give a resistance proportional to the solenoid pull, and consequently an even retarding effect is obtained throughout the range of movement of the signal.

My invention will best be understood by reference to the accompanying drawings, in which

Figure 1 shows an elevation of a signal mechanism arranged in accordance with my invention; Fig. 2 shows a diagram of the circuit connections; Fig. 3 shows an enlarged front elevation of the locking magnet; Fig. 4 is an explanatory diagram of the dash-pot resistance; and Fig. 5 shows a cross-section of one dash-pot.

In Fig. 1, A represents a vertically movable rod operatively connected at its upper end to the semaphore arm, which is not shown in this figure. The signal is arranged in the usual manner to go to danger by gravity. When the signal is at danger the rod A is in its lowest position, as shown in Fig. 1. Two magnets B and C are provided for lifting the rod A to move the signal to caution and to clear positions, respectively. The core of the magnet B is connected to a pivoted lever b which is connected in turn through a pin and slot connection to a sleeve a loosely surrounding the vertical rod A and supporting this rod in the position shown by means of a collar a' which is fast to the rod and rests on top of the sleeve a. The core of the magnet C is similarly connected to a pivoted lever c, which is directly connected to the vertical rod A. When the solenoid B is energized it raises its core, thereby raising rod A by means of the sleeve a and collar a'. This movement of rod A also raises lever c and the core of the solenoid C, so as to bring this core into position to be attracted effectively by the solenoid C. The signal is thus brought to caution position. When the

solenoid C is energized it raises its core still further, thereby raising rod A so as to shift the signal from caution to clear position. This movement of rod A does not move the lever b or core of solenoid B, since the rod A slides freely upward through the sleeve a.

D' and D² are dash-pots which are connected through the levers b and c to the cores of solenoids B and C, respectively. The purpose of employing two dash-pots is shown by Fig. 4, which represents diagrammatically the retarding effect exerted by two separate dash-pots compared to the retarding effect which would be exerted by a single dash-pot. In this figure the curve 1 represents approximately the resistance offered by an air dash-pot to the movement of the piston in the range of its travel, the abscissas representing the distances moved and the ordinates representing the forces opposed by the dash-pot to this movement. It will be seen that the curve is similar to the curve of the pull exerted by a solenoid, so that if a single dash-pot and solenoid are employed a very uniform retarding effect is produced. If, however, two solenoids are employed to shift the signal, the pulls exerted on the signal during the course of its movement will be represented by the two curves 2 and 3. It will be seen that a single dash-pot, having a retarding effect as shown by curve 1, would produce an uneven retardation of the signal. By employing two separate dash-pots, each dash-pot may be designed to approximate the characteristic of the solenoid, so that the curves 2 and 3 may represent both the pulls exerted on the signal by the solenoids, and the retarding effects of the dash-pots, so that an even retardation is obtained over the entire range of movement. The dash-pot D² is constructed as shown in Fig. 5, so that although it moves during both movements of the signal, it does not begin to act as a dash-pot until the second movement of the signal.

E represents the locking magnet which, when energized, attracts the armature e, which is arranged with a link connection so that when it is attracted it straightens out the toggle-joint formed by the links e', so as to press the latch e² against rod A. This rod is notched at two places which are brought opposite the latch e² when the signal is at caution and at clear position, respectively. Consequently, when the signal is at either of these positions and the magnet E is energized the signal will be firmly locked in position. The latch e² and the notches in the vertical rod A are beveled so that whenever the magnet E is deenergized the rod will push the latch out of the way and drop to danger position. The magnet E is designed for operation with alternating-current, and consequently is preferably provided with a laminated core, as shown in Figs. 1 and 3, and its armature is also laminated, as shown

in Fig. 1. The core of magnet E carries on the face of the poles of the core short-circuited conductors e^3 , each of which surrounds a portion of the pole-face, as shown in Fig. 3. 5 These conductors produce a phase displacement between the fluxes in the two portions of the pole so that the magnet is never without flux. This construction avoids all tendency to chatter or to release the signal, and 10 consequently enables the lock-magnet to hold the rod in place with a smaller amount of current than would be required if the short-circuited conductors e^3 were not employed. The vertical rod A carries an arm 15 F on which are mounted a number of electrical contacts which move over the stationary contacts f^3 as the signal is shifted. By means of these stationary contacts the circuits of the lifting magnets and lock-magnets are 20 controlled in the proper manner.

The construction of the signal having been explained, the operation will be readily understood by referring to Fig. 2. While my invention is not limited to any particular arrangement of circuit connections, I have shown a complete diagram of circuit connections in order that my invention may be more clearly understood. In Fig. 2 an electrically-operated road is shown in which both 25 rails are sectioned to form the block signal track circuits. Three of the block circuits are indicated by the reference letters R' , R^2 and R^3 , and the reference letters applied to the signal mechanism for each block are the 30 same as those in Fig. 1, with the addition of exponents corresponding to the number of the block to which they relate. R represents the third rail or other supply-conductor which carries the power-current for propelling the vehicle. In the present case this 35 current is assumed to be direct. L represents line-wires carrying alternating-current for supplying the signal current to the track circuit. The track circuit formed of the 40 rails R' is supplied from the line-wires L through the transformer T^2 . At the other end of the block the primary of a transformer t' is connected across the rails, while a relay r' is connected to the secondary of the 45 transformer. The relay r' shown is of the two-phase induction motor type, one phase being supplied from the track transformer t' , and the other directly from the line-wires L . The moving member is a short-circuited 50 conductor carrying the necessary contacts. In order that the rails may serve as a return conductor for the power-current, as well as forming the track circuit for the block signal system, the middle points of the transformer 55 windings connected to adjacent ends of adjacent blocks are connected to each other. By means of this connection, as explained in Patent No. 645,907, Bedell, issued March 20, 1900, the two currents flow through the same 60 conductors without interference with each

other. A car or train is indicated in the block R^3 and the signal S^3 for that block is consequently shown at danger position, while the signals S^2 and S^1 are shown at caution and at clear positions, respectively. 70 For the sake of convenience in diagrammatic illustration the vertical operating rods for the signals are shown as moving downward to clear the signal, whereas in the actual construction shown in Fig. 1 the rod moves upward to clear. This difference is of course immaterial.

The electric circuits and the operation of the systems are as follows: With a train in the block R^3 , as shown, the primary of transformer t^3 is short-circuited so that one phase of the relay r^3 is deenergized, and consequently the relay contacts are opened. The circuits of operating magnets B^3 and C^3 and of lock-magnet E^3 are all open. When the 80 train passes out of block R^3 both phases of the relay r^3 are again energized and the relay is moved so as to close the contacts which it controls. A branch circuit from the power-circuit is then closed from the third rail R through the contacts of the relay r^3 , through switch contacts F^3 , and through the magnet B^3 to the track rails. Magnet B^3 is consequently energized by power-current and draws in its core, thereby shifting the signal 85 to caution position. When caution position is reached, as shown at the signal S^2 , the circuit of operating magnet B^2 is broken at the contacts F^2 , so that the movement of the signal is stopped. At the same time the circuit 90 of the locking magnet E^2 is closed as follows: from the lower line-wire L , through magnet E^2 , through switch contacts F^2 , through the back contact of the three-position relay o^2 , which is controlled by the following signal S^3 , 95 through contacts of track relay r^2 , to the upper line-wire L . Lock-magnet E^2 is consequently energized to hold the signal in caution position. When the train leaves the 100 block R^3 the three-position relay o^2 is energized by the movement of the track relay r^3 to closed circuit position. Consequently it 105 raises its core, shifting its contacts. This movement of the contacts breaks the circuit of the locking magnet E^2 and closes the circuit of the operating magnet C^2 as follows: from the third rail R through contacts of the 110 relay r^2 , through contacts F^2 controlled by the signal, through contacts of relay o^2 , through the winding of magnet C^2 to the track rails. Magnet C^2 consequently draws in its core, shifting the signal from caution to clear position. When clear position is 115 reached, as shown at the signal S^1 , the circuit of the operating magnet C^1 is broken at the contacts F^1 controlled by the signal, while the circuit of the lock-magnet E^1 is closed 120 through contacts F^1 and front contact of the three-position relay o^1 and contacts of track relay r^1 . The signal is consequently locked 125 130

at clear position and is held there until another train comes into the block.

It will be seen that the work of shifting the signal is done by magnets operated from the power-circuit. On a road operated by direct-current these magnets may consequently be direct-current solenoids of high efficiency. On the other hand, since the lock-magnets are supplied from the signal circuit an interruption of the power-circuit will not release the signals. Both relays are also actuated by the alternating-current so that disturbances in the power-circuit cannot affect a signal that has been properly cleared and locked.

What I claim as new and desire to secure by Letters Patent of the United States, is,—

1. In a signal for electrically-operated roads employing separate circuits for the power-current and signal-current, means for shifting the signal mechanism operated by power-current, and means operated by current from the signal circuit for locking the signal when shifted.

2. In a signal for electrically-operated roads employing separate circuits for the power-current and signal-current, a magnet for shifting the signal mechanism supplied with current from the power-circuit, and a magnet supplied with current from the signal circuit for locking the signal when shifted.

3. In a signal for electrically-operated roads employing separate circuits for the power-current and signal-current, a magnet for shifting the signal mechanism connected on a branch from the power circuit, and a magnet connected in a branch from the signal circuit for locking the signal when shifted.

4. In a signal for electrically-operated roads employing a direct-current power-circuit and an alternating-current circuit for supplying signal-current to the track circuits, means energized by direct-current for shifting the signal mechanism, and means energized by alternating-current for locking the signal when shifted.

5. In a signal for electrically-operated roads employing a direct-current power circuit and an alternating-current circuit for supplying signal-current to the track circuits, a magnet for shifting the signal mechanism connected in a branch from the direct-current power-circuit, and a magnet connected in a branch from the alternating-current supply-circuit for locking the signal when shifted.

6. In an electrically-operated road having both rails sectioned to form blocks, an alternating-current circuit, transformers supplying current from said circuit to the rails of each block, transformers having their primaries connected to the rails of the several blocks, relays connected to the secondaries of the last-mentioned transformers, elec-

trical connections between the middle points of the rail circuit windings of the transformers at the adjacent ends of adjacent blocks to furnish a return circuit for the power-current, means controlled by the relay of each block 70 for shifting the signal of that block and energized by power-current, and means also controlled by said relays for locking the signals when shifted; said locking means being energized by current from the alternating-current supply-circuit.

7. In an electrically-operated road having both rails sectioned to form blocks, an alternating-current circuit, transformers supplying current from said circuit to the rails of each block, transformers having their primaries connected to the rails of the several blocks, relays connected to the secondaries of the last-mentioned transformers, electrical connections between the middle points of the rail circuit windings of the transformers at the adjacent ends of adjacent blocks to furnish a return circuit for the power-current, magnets connected in branches from the power-circuit and controlled by the relays 90 for the several blocks and adapted to shift the signals for said blocks and magnets connected in branches from the alternating-current supply-circuit and also controlled by said relays, and locking means for the signals 95 controlled by the alternating-current magnets.

8. In combination, a magnet core, an energizing coil therefor supplied with alternating-current, a short-circuited conductor surrounding a portion of the face of a pole of said core, an unwound laminated armature of magnetic material movable in a direction substantially perpendicular to the face of said pole by magnetic attraction, and mechanism actuated by the movement of said armature.

9. In a signal, a magnet core, an energizing coil therefor supplied with alternating-current, a short-circuited conductor surrounding a portion of the face of a pole of said core, an unwound laminated armature of magnetic material movable by magnetic attraction in a direction substantially perpendicular to the face of said pole, and signal controlling means actuated by the movement of said armature.

10. In a signal, operating means for shifting the signal, and a magnet for locking the signal when shifted comprising a laminated core, an energizing coil thereon supplied with alternating-current, a short-circuited conductor surrounding a portion of the face of a pole of said core, and an armature adapted to be moved toward the face of said core by 120 magnetic attraction.

11. In a signal, a signal-arm movable to three positions, two independent solenoids for shifting said arm to caution and to clear respectively, and two dash-pots operatively 130

connected to the respective cores of said solenoids.

12. In a signal, a signal-arm movable to three positions, two independent solenoids, connections between said magnets and said arm whereby said arm is shifted to caution when one solenoid is energized and from caution to clear without moving the core of said solenoid when the second solenoid is ener-

gized, and two dash-pots operatively connected to the respective cores of said solenoids.

In witness whereof, I have hereunto set my hand this 16th day of February, 1906.

FRED B. COREY.
